OLIVER J. MOUSSETTE, OF RICHMOND HILL, NEW YORK.

OIL BURNER.

Application filed February 19, 1925. Serial No. 10,401.

This invention relates to oil burners and has for its object the provision of a simple burner which may be easily placed within the fire-box of an ordinary furnace and operated economically and without the noises incident to the use of many oil burners now upon the market. The invention seeks to provide a burner which may be easily assembled and which will be so constructed that the oil will be thoroughly vaporized and will be commingled with air so as to produce an intense flame of wide spread which will burn without depositing any carbon, and the invention also seeks to provide a burner in which, when installed, all the air flowing thereto will be directed to the points where it will meet the vaporized oil in such manner that a thorough commingling of the vapor and the air will be effected and perfect combustion result. These stated objects, and other objects which will incidentally appear in the course of the following description, are attained in such a device as is illustrated in the accompanying drawings and the invention resides in certain novel features which will be particularly pointed out in the appended claims.

In the drawings:

Figure 1 is a vertical section of a burner embodying my invention as installed within the fire-box of a furnace;

Fig. 2 is a plan view of the burner with the burner plates removed;

Fig. 3 is a top plan view of the burner plates;

Fig. 4 is a bottom plan view of the lower burner plate, and

Fig. 5 is an enlarged detail section on the line 5—5 of Fig. 2.

In the drawing, the reference numeral 1 indicates a portion of the shell of a furnace, and 2 the usual grate installed in said shell and constituting the bottom of the fire-box.

In carrying out my invention, I provide a base plate 3 which may be of any convenient form and is illustrated in Fig. 2 as substantially elliptical to facilitate its insertion through the ordinary fuel door of the furnace. This base plate is provided with a de-

pending marginal rim 4 adapted to rest upon the grate 2 in spaced relation to the shell 1 and thereby provide an outer chamber which receives cement or other plastic material, indicated at 5, so that there can be

only a restricted circulation of air through the furnace around the base plate and nearly all air entering the ash pit or the space below the grate 2 will be directed into the chamber defined by the depending rim 4. The central portion of the base plate is depressed or beveled inwardly and downwardly, as indicated at 6, so as to provide a ring or flange having a central opening constituting a passage for the air flowing thereto through the grate 2. The central opening is seen most clearly at 7 in Fig. 2, and it will be noted that the available portion of the central opening takes the form of a relatively narrow arcuate slot, the inner wall of which is defined by an annular plate or spider 8 having radially extending lugs or arms 9 projecting at intervals from its edge under the ring 6 and preferably formed integral with the latter. The annular plate or ring 8 is formed in its upper face or top side with concentric grooves 10 and 11, the outer one of which, 10, is adapted to receive and hold a wick 12 of asbestos or similar material whereby oil delivered into the inner groove 11 will be confined to said groove and will not be permitted to overflow the ring onto the grate and be lost or constitute a fire menace. Oil is supplied to the groove 11 through an auxiliary feed pipe 13 which has its end threaded into a nipple 14 on the under side of the spider or circular plate at any convenient point thereof, the bore 15 of said nipple or boss opening through the bottom of the groove 11, as seen most clearly in Fig. 5.

The annular plate 8 which constitutes an ignition pan also furnishes a support for the burner plates, the lower burner plate 16 being circular in plan view and being provided on its under side with spaced lugs 17 and 18 which are adapted to rest upon the edge of the circular plate 8 at the inner side of the groove 11, as shown in Fig. 1. As will be understood upon reference to Figs. 1 and 4, the lugs 17 and 18 are formed to define shoulders 19 which will engage the edge of the annular plate 8 and thereby maintain the concentric relation of said plate and the burner plate, and the lugs 17 are provided at their inner sides with threaded sockets 20 to receive securing screws or bolts 21 which are inserted upwardly through a clamping bar 22 into the said sockets, as

shown clearly in Fig. 1, whereby the burner plate will be secured firmly in place, it being understood that the ends of the clamping bar bear against the under side of the 5 annular plate or ignition pan 8. Upon reference to Fig. 2, it will be noted that the bar 22 is relatively narrow so that there is an open space through the central portion of the plate 8 and at the sides of the clamping bar for the circulation of air. The oil supply pipe 23 may be carried into the furnace from a distant point of supply through the ash pit of the furnace or through an opening provided especially therefor in the 10 shell of the furnace, but in any event it is provided at its inner end with a vertical delivery branch 24 passing upwardly through the grate 2 and through a central opening 25 of the clamping bar 22 to engage a central 15 opening in the burner plate 16, the end of said branch and the burner plate being provided with external and internal threads whereby the pipe may be firmly secured in the plate. Referring particularly to Fig. 20, it will be noted that the lower burner plate is constructed with a central conical portion 26 so that the oil escaping from the pipe 24 will flow outwardly and downwardly and tend to collect in the annular channel 27 formed in 25 the plate at the base of the conical portion 26. The outer wall of this channel is formed by a circular rib 28 upon the upper side of the burner plate at the edge thereof and of less height than the central conical portion 26. 30 At intervals upon the edge of the burner plate are lugs 29 which constitute spacers to hold the lower burner plate 16 and the upper burner plate 30 out of contact and thereby provide a passage through which 35 the vaporized oil may escape. The upper burner plate 30 has a cross sectional form conforming to the lower plate and presents a central conical portion 31 which is of greater diameter than the conical portion 26 and also of greater height than the said portion 26 whereby a considerable space will occur between the two burner plates, as 40 shown in Fig. 1. At the base of the conical portion 31, the upper burner plate has a short annular web 32 extending substantially parallel with the floor of the channel 27 in the lower burner plate and is then formed with an annular substantially V-shaped rib 33 fitting over the rim or rib 28. The outer 45 web of the rib 33 extends downwardly and outwardly and converges slightly toward the edge of the lower burner plate so that the inner surface of this wall will rest upon the lugs 29, as shown in Fig. 1. From the 50 lower edge of this outer wall of the rib 33, there extends a circular marginal portion 34, the radius of which is nearly equal to the radius of the ring 6 below it. This web or plate 34 extends upwardly and outwardly 55 from the lower edge of the rib 33, as clearly

shown in Fig. 1, and is substantially parallel to the upper surface of the ring 6 so that a passage is provided for the air flowing through the slot 7 and through the space below the lower burner plate. The slot 7 70 is located radially beyond the lugs 29 and the space defined by said lugs so that the air rising through the slot will mingle with the vapor at a point beyond its point of emission from the burner plates, the greater body 75 of air passing upwardly from the center of the ignition pan or plate 8 and flowing laterally from below the lower burner plate. Disposed concentrically about the upper burner plate is a silencer consisting of a rim or ring 35 resting upon the grate 2 and a perforated plate 36 extending inwardly from and carried by its upper edge, an inner ring 38 being between and concentric with the rim 4 and the ring 35. The space between 80 the ring 38 and the rim 4 is sealed with the cement 5 but an open air passage 39 is left between the rings 35 and 38. It will be noted that the upper burner plate is not fixed to the silencer nor to the lower burner plate 85 but simply rests upon the lugs 29 on the lower burner plate. This manner of supporting the upper burner plate facilitates its removal in the event that cleaning or 90 inspection of the device is necessary, and to aid removal or replacement a ring or eye 95 37 is formed on the plate at its center, which eye or ring may be easily engaged by any form of withdrawing tool or may be simply lifted by hand. All the parts may be made 100 in mating halves to facilitate insertion through the fuel door of the furnace. When the burner is to be used, a sufficient quantity of oil to fill the groove 11 is permitted to flow into said groove through the 105 branch supply pipe 13, the flow being cut off when the oil reaches the top of the wick 12. This initial supply of fuel is ignited, and it will make a flame sufficient to heat the 110 burner plates and effect initial vaporization 115 of any fuel which may be permitted to flow through the supply pipes 23 and 24. When the initial supply of fuel in the groove 11 has been consumed, the flow of fuel through the pipes 23 and 24 is permitted, and this fuel will overflow down the conical portion 26 of the lower burner plate and eventually escape through the space between the burner plates and the lugs 29. As the vapor issues 120 from the said space, it will be ignited and the flame and the heat therefrom will then rise through the perforations of the plate 36 and act upon the walls of the furnace fire-box to heat the same in the same manner 125 that a coal fire ordinarily would perform that work. Experience has demonstrated that by supplying the air to the vapor in the manner shown and described through the space below the burner plate and also 130 through the slots 7, a thorough commingling 130

of the air and the oil vapor is effected, and this vapor will be completely consumed without any deposit of carbon upon any of the parts of the device. Moreover, by interposing the perforated silencer plate 36 around the burner and confining the flame and heat so that it can escape only through the perforations of said plates, I have eliminated the exceedingly disagreeable noise 10 which is incidental to the use of most oil burners now upon the market. My device is exceedingly simple in the construction and arrangement of its parts, may be easily assembled and installed in any furnace and 15 may be operated very economically.

Having thus described the invention, I claim:

1. In an oil burner, the combination of upper and lower burner plates, means for 20 supplying oil to the space between said plates to be burned as it issues therefrom, and a silencer consisting of an imperforate rim concentrically surrounding the burner plates in radially spaced relation thereto and 25 a plate perforated throughout its area extending from the upper edge of said rim to the burner plates and having a central opening within which the upper burner plate fits.

2. In an oil burner, the combination of 30 a supporting plate having air openings therethrough, a lower burner plate carried by said supporting plate in vertical spaced relation thereto, a clamping plate bearing 35 against the under side of said supporting plate, securing devices inserted through the clamping plate free of the supporting plate and engaged in the burner plate, means independent of the securing means for supplying fuel to the burner plate, and an upper burner plate supported upon the lower 40 burner plate in spaced relation thereto.

3. In an oil burner, the combination of 45 a supporting plate having a central opening for the passage of air and provided with arcuate slots extending vertically therethrough concentric with said central opening and spaced outwardly therefrom, a lower burner plate provided with depending 50 spaced lugs resting on the inner edge of the supporting plate, a clamping bar bearing at its ends against the under side of the supporting plate, fastening devices inserted through said clamping bar into some of the 55 lugs on the burner plate, and an upper burner plate conforming to the lower burner plate and supported at the edge of the lower burner plate in spaced relation thereto, the space between the burner plates 60 having a radius greater than the central opening through the supporting plate and less than the arcuate slots in the supporting plate.

4. In an oil burner, the combination of a 65 circular ignition pan having concentric an-

nular grooves in juxtaposition in its upper surface the outer groove being deeper than the inner groove, a fire-resisting wick upon the pan in the outer groove, an oil supply opening into the bottom of the inner groove, 70 and upper and lower burner plates supported by said ignition pan and disposed above the same, the upper burner plate having a marginal portion overhanging the pan.

5. In an oil burner, the combination of a base plate having a depending rim to rest upon a furnace grate, a central ignition pan carried by said base plate and connected therewith in spaced relation thereto, burner 75 plates supported by and disposed above said ignition pan, a silencer plate disposed above the base plate around the burner plates a rim supporting the silencer plate and resting on the furnace grate, an intermediate 80 ring between and concentric with the said rim and the rim of the base plate, and a sealing filler between the shell of the furnace and the rim supporting the silencer plate and between the rim of the base plate and 85 the intermediate ring.

6. In an oil burner, the combination of a supporting plate having air openings therethrough, a lower burner plate carried by 90 said supporting plate in vertically spaced relation thereto, a clamping plate bearing against the under side of said supporting plate, securing devices inserted through the clamping plate free of the supporting plate and engaged in the burner plate, means independent of the securing devices for supplying fuel to the burner plate, and an upper burner plate supported upon the lower 95 burner plate in spaced relation thereto, the upper burner plate having a marginal portion extending beyond the lower burner plate and overhanging the supporting plate 100 in approximately parallel relation thereto.

7. In an oil burner, the combination of a base plate having a depending imperforate rim adapted to rest upon a furnace grate, the base plate having a central opening therethrough and having a downwardly inclined annular portion leading to said opening, an annular ignition pan disposed within said opening in spaced relation to said downwardly inclined portion of the base plate and supported thereby, the pan having concentric grooves in its upper side and having 110 its upper side at its edge flush with the upper side of the downwardly inclined portion of the base plate, a wick in the outer groove, means for supplying fuel to the inner groove, a lower burner plate disposed above the ignition pan, means cooperating with the inner marginal portion of the ignition pan and the bottom of the burner plate to clamp the burner plate to the ignition pan in vertically spaced relation, an upper burner plate disposed over and mating with the 115 120 125 130

lower burner plate and supported at the margin of the latter in spaced relation thereto, the space between the burner plates diminishing vertically from their centers to their edges and the upper burner plate having an upwardly and outwardly extending margin overhanging the downwardly inclined portion of the base plate and parallel therewith, and means for supplying fuel to the space between the burner plates at the center thereof.

In testimony whereof I affix my signature.

OLIVER J. MOUSSETTE. [L. s.]
